(57) CLAIM

The ornamental design for heel for footwear, as shown and described.

DESCRIPTION

FIG. 1 is a front perspective view of a shoe showing my heel design;

FIG. 2 is a bottom perspective view of the heel shown in FIG. 1;

FIG. 3 is a left side view of the heel shown in FIG. 1;

FIG. 4 is a right side view of the heel shown in FIG. 1;

FIG. 5 is a rear view of the heel shown in FIG. 1; and,

FIG. 6 is a bottom view of the heel shown in FIG. 1.

The broken line showing of the shoe upper, buckle, buckle holes, heel cap, foot bed, platform sole, and sole is for illustrative purposes only and forms no part of the claimed design.
